UNITED STATES PATENT OFFICE

GERALD J. HENRY, OF BOSTON, AND KENNETH A. SAWIN, OF WINTHROP, MASSACHUSETTS, ASSIGNEES TO WHEELER REFLECTOR COMPANY, OF BOSTON, MASSACHUSETTS, A CORPORATION OF MASSACHUSETTS

ELECTRIC-LIGHT FIXTURE

Application filed October 22, 1927. Serial No. 227,920.

This invention relates to electric light fixtures and particularly those used for outdoor illumination, and it has for its object to provide certain improvements in electric light fixtures by which the structure of the fixture is simplified and the assembly of the parts and wiring of the fixture is facilitated.

In order to give an understanding of the invention we have illustrated in the drawings a selected embodiment thereof which will now be described after which the novel features will be pointed out in the appended claims.

Fig. 1 is a view partly in section illustrating our invention as applied to electric light fixtures, especially designed for billboard lighting;

Fig. 2 is a fragmentary perspective view of the upper end of the neck of the reflector;

Fig. 3 is a bottom plan view of the upper section of the socket;

Fig. 4 is a section on the line 4—4, Fig. 5;

Fig. 5 is a section on the line 5—5, Fig. 4.

The electric light fixture herein shown is of that type which comprises a cap or canopy member, a socket member secured to the canopy member and a reflector member also secured to the cap or canopy member.

In the drawings 1 indicates the cap member, 2 the socket member which supports the electric light bulb 3 and 4 is the reflector member.

The cap or canopy member 1 is preferably of cast metal and it is provided with a boss 5 into which is secured a supporting pipe 6 by which the structure is supported and which also serves as a conduit for receiving the wires 7. This boss 5 may be arranged either vertically or horizontally as desired and in the construction shown it is arranged horizontally so that the supporting pipe will extend in a horizontal direction.

The socket member 2 is of the type comprising the upper section 8 and the lower sleeve section 9. The upper section 8 carries the lamp terminals 10, 11, the latter being in the form of the usual screw-threaded neck into which the lamp 3 is screwed and the former being a spring terminal which the end contact of the bulb 3 engages. The terminals 10, 11 have the usual binding screws 12, 13 to

which the wires 7 are attached in usual manner.

The sleeve member 9 is loosely screw threaded to the exterior of the screw-threaded terminal 11 and is for the purpose of covering the contact members.

The socket member 2 is constructed so that it can be readily attached to or detached from the cap member 1. The cap member 1 is provided with two bosses 14 against which the socket member rests, each boss carrying an attaching screw 15. The socket member is provided with two openings 16 of a size to receive the heads 17 of the attaching screws and each opening 16 has communicating therewith a slot 18 of a size to receive the shanks of the screws.

In assembling the socket member with the cap member the heads 17 of the screws are entered through the openings 16 and then the socket member is given a partial turn to bring the shanks of the screws into the slots 18. The socket member is shown as counterbored at 19 so that the heads of the screws are below the lower surface of the member 18. After the socket member 2 has been placed in position the screws 15 may be tightened slightly if desired to frictionally hold the socket member in position.

The cap member 1 is provided with a depending skirt portion or flange 20 which carries the means for supporting the reflector 4. This reflector is provided with the neck portion 21, the upper edge of which is formed with the bead or rib 22. The skirt 20 has projecting inwardly therefrom two projections 23 and the upper end of the neck 21 is provided with two vertical slots 24 which have the same relative arrangement as the projections 23.

In assembling the reflector with the cap member 1 the upper end of the neck is inserted into the skirt with the lugs 23 in alignment with the slots 24 so that said lugs will enter the slots. When the upper end of the neck is against the under face of the cap with the bead 22 above the projections 23 then the reflector is given a partial turning movement to disalign the slots 24 and the projections 23.

The projections 23 are then situated beneath the rib 22 as shown in Fig. 5 so that the reflector is supported by the lugs.

In order to lock the reflector in position we have shown a set screw 34 which is carried by the flange 20 of the cap 1 and which is adapted to engage a seat member 25 that is carried by the neck 21 of the reflector. The reflector may conveniently be made of sheet metal which is provided interiorly with the proper reflecting surface and the seat member is shown as a button-like element which is rigidly secured to the upper end of the neck 21 in some suitable way. One way is to make this seat member in the form of a rivet which extends through the wall of the neck and is headed over on the inside thereof as shown at 26.

The skirt portion 20 of the cap or canopy may conveniently be formed with a recess 27 in which the seat member 25 is received.

In assembling the reflector the upper end of the neck 21 will be entered into the skirt 20 with the parts in the position shown by dotted lines Fig. 4, in which position the slots 24 are in line with the projections 23. After the upper edge of the neck 21 is resting against the under face of the cap 1 then the reflector is given a turning movement to bring it into the full line position Fig. 4 which will bring the seat 25 into alignment with the set screw 34 and will disalign the slots 24 from the projections 23. When the set screw 34 is tightened against the seat member 25 the reflector will be firmly locked in position.

If it is desired to remove the reflector for any purpose such for instance as to repair the wiring or otherwise this can be done by simply loosening the set screw 34 and then turning the reflector into the dotted line position Fig. 4 thereby to bring the slots 24 into alignment with the projections 23 after which the reflector is free to be withdrawn from the cap member.

45 We claim:

In an electric light fixture, the combination with a cap member having a depending annular flange provided with inwardly-extending projections, of a socket member secured to said cap member, a reflector member having a neck portion provided with a bead or rib at its upper end, said bead or rib being provided with slots having the same relative arrangement as the projections, whereby the reflector member may be secured to the cap member by entering the end of the neck portion into the annular flange with the projections occupying the slots and then turning the reflector to disalign the projections and slots, a seat member carried by the neck and extending outwardly therefrom and a locking screw carried by the flange and adapted to engage the seat member and thereby lock the reflector from turning movement, said flange having a

recess on its interior face to receive the seat member as the parts are being assembled.

In testimony whereof, we have signed our names to this specification.

GERALD J. HENRY.
KENNETH A. SAWIN.
